UNITED STATES PATENT OFFICE.

MILTON W. BECHTEL, OF WARREN, OHIO, ASSIGNOR TO THE BORDEN COMPANY, OF WARREN, OHIO, A CORPORATION OF OHIO.

DIE-STOCK.

1,304,249.

Specification of Letters Patent. Patented May 20, 1919.

Application filed April 4, 1917. Serial No. 159,654.

To all whom it may concern:

Be it known that I, MILTON W. BECHTEL, a citizen of the United States, residing at Warren, in the county of Trumbull and State of Ohio, have invented a certain new and useful Improvement in Die-Stocks, of which the following is a full, clear, and exact description, reference being had to the accompanying drawings.

10 This invention relates to a die stock of the type wherein the chasers are rigid in a holder during operation. The object of the invention is to provide in a very simple and efficient form a die stock of this character, having the chasers carried as a unit by a holder removable from the frame, enabling the ready interchange of different sets of chasers for different sizes of pipes to be threaded. My invention provides a 20 chaser-carrying frame which also acts as the bushing for guiding the die stock about the pipe, this frame being removable from, but readily locked to, the handle frame by which the die stock is turned. The invention is hereinafter more fully explained, and its essential characteristics are summarized in the claims.

In the drawings, Figure 1 is a front elevation of my die stock; Fig. 2 is a rear elevation thereof; Fig. 3 is an edge view, being a plan of the die stock with the handles horizontal; Fig. 4 is a side elevation of the chaser-carrier, detached; Fig. 5 is a radial section through the die stock, as indicated by the line 5—5 on Fig. 1; Fig. 6 is a vertical section through the chaser-carrier, in a plane parallel with Fig. 1, as indicated by the line 6—6 on Fig. 4; Fig. 7 is a vertical section in a plane parallel with Fig. 1, 40 looking toward the front.

The main frame of my die stock, designated 10, consists of a substantially parallel-sided block having an internal cylindrical chamber 11 overhung at the front by an integral flange 12 of the block. The frame is provided with diametrically opposite sockets 13, which are internally threaded to receive operating handles 25. The frame is also provided with a radial housing 16 for a locking plunger, to be hereinafter described. The sockets and housing are braced by suitable stiffening webs 17. The whole frame may conveniently be one single integral casting.

55 The cylindrical chamber within the frame

is normally partially closed at the rear by a circular ring 20, seated within the frame and held in place by screws 21 passing through the body of the frame. The internal diameter of the ring 20 is preferably 60 the same as that of the flange 12.

The chasers are indicated at 30. They are substantially rectangular blocks having cutting teeth 31 at their inner edges and having holes 32 through them. These chasers are rigidly mounted in radial guideways in the chaser-carrying frame 40, being locked thereto by screws 35 passing through the holes 32.

The chaser-carrying frame has a cup-like 70 head 41 with a front flange 42 and pairs of radial webs 45 providing between them the chaser guideways. The screws 35 extend through these radial webs and lock the chasers in place. The chaser-carrying frame has 75 a sleeve 46 which projects to the rear of the head and is adapted to extend into the handle frame and be locked thereto, as herein-after described. In external diameter the sleeve corresponds to the internal diameter 80 of the flange 12 and ring 20; in internal diameter it corresponds to the external diameter of the pipe to be threaded. This sleeve accordingly acts as the bushing guiding the die stock on the pipe. 85

To effectively lock the chaser frame to the handle frame, and at the same time allow the ready removal of the chaser frame, I provide the following construction:

Within the chamber of the handle frame 90 is a movable ring 50, having a cylindrical inner and outer periphery. In the inner periphery of this ring are grooves 52 parallel with the axis of the die stock. I have shown two of these grooves diametrically opposite. The sleeve of the chaser frame is provided with a pair of correspondingly positioned ribs 48, which may be integral with the sleeve. These ribs are adapted to be shoved into place in the grooves when the 100 grooves are positioned opposite a pair of notches 19 in the handle frame. The ribs on the chaser frame are separated from the plate portion 43 thereof by a distance corresponding to the thickness of the flange 12. 105 Accordingly, if the sleeve of the chaser frame is shoved into the handle frame, the ribs 48 passing through these notches 19, and the chaser frame then given a partial rotation, it is held against pulling out by 110

reason of the ribs passing behind the flange 12. Accordingly, if I lock the ring 50 in position after such partial rotation has been made, the chaser carrier is rigidly locked to 5 the handle frame.

To lock the ring 50 to the handle frame, as above referred to, I provide a plunger 60 slidably mounted in the radial housing 16. This plunger is carried in a bushing 62 10 screwed into the interior of the housing, and is pressed inwardly by a spring 63 surrounding the shank of the plunger and compressed between the bushing and a head 64 on the plunger. A boss or lug 65 on the inner end 15 of the plunger is adapted to seat in a notch 51 in the ring 50, this notch being so positioned that when it is in registration with the plunger the grooves 52 are out of registration with the notches 19. To operate the 20 plunger I provide it with a suitable handle 67, which may conveniently be a plate occupying a kerf in the plunger 60 and riveted thereto. In the locked position this handle occupies diametrically opposite notches 68 25 in the housing, and in such position the boss occupies the notch 51 and thus locks the ring and thereby the chaser frame to the handle frame.

To remove the chaser frame, it is only necessary to grasp the head of the plunger 60 30 and draw it out and give it a partial turn. This causes the inner edge of the handle 67 to bear against the end of the housing and hold the boss out of the notch 51. This frees 35 the ring 50. Thereupon the chaser frame may be grasped by the hand and given a partial rotation until the ribs thereof come opposite the notches 19, whereupon the chaser frame may be drawn axially outwardly and separated from the handle 40 frame.

It will be seen that chaser frames of different internal bore and chasers having teeth for different sized pipes may readily be used 45 with the same handle frame, it being only necessary that the exterior of the sleeve portion of the chaser frame correspond to the interior of the handle frame and locking ring. This makes a very simple and readily interchangeable construction. The device is also 50 very compact. The sleeve portion of the chaser-carrier takes the place of a separate bushing, or other means, for guiding the die stock. The head of the chaser-carrier is enlarged or cupped out, sufficiently to provide 55 space for chips and for the ready oiling of the cutting teeth.

Having thus described my invention, what I claim is:

60 1. The combination of a rotary frame having an internal chamber, a ring within said chamber, a chaser frame having a sleeve adapted to extend into said ring, a key-and-groove connection between the 65 chaser frame and ring, means for preventing

the separation of the chaser frame and ring in certain positions of the ring, and means for positively locking the ring in one of such positions, and chasers carried by the chaser frame.

70

2. In a die stock, the combination of a rotary frame having a cylindrical cavity, a ring having a cylindrical inner and outer periphery and occupying said cavity, said ring having an external notch, a plunger 75 adapted to occupy said notch and positively lock the ring against movement in either direction, a chaser frame having a sleeve adapted to closely occupy the interior of the ring, said sleeve having a rib on its exterior 80 and the ring having a groove to receive the rib, said rotary frame having a flange adapted to overhang the outer end of said rib, there being a notch through said flange adapted to align with the internal groove in 85 the ring when the external notch in the ring is out of alignment with the plunger, and a chaser carried by said chaser frame.

3. The combination of a handle frame having a pair of diametrically opposite 90 sockets, handles occupying said sockets, said handle frame having an internally cylindrical chamber overhung at the front by a flange having a notch, a movable ring within the chamber and having a notch in its outer 95 periphery, a radial housing carried by the frame, a plunger mounted in said housing and having its inner end adapted to occupy the external notch in the ring and prevent movement thereof in either direction at a 100 time when an internal groove in the ring is out of registration with the notch through said flange, a chaser frame having a cylindrical sleeve adapted to occupy said movable ring and having an external rib adapted to 105 pass through the notch in the flange into the internal groove of the movable ring, said rib being adapted to pass behind the flange when the movable ring is turned about its axis, and chasers carried by the chaser 110 frame.

4. The combination of a handle frame having a pair of diametrically opposite sockets, handles occupying said sockets, said handle frame having an internally cylindrical chamber overhung at the front by a flange integral with the frame and overhung at the rear by a ring removably secured to the frame, a movable ring within the chamber specified and having an abrupt notch in 115 its outer periphery, a radial housing carried by the frame, a spring-pressed plunger mounted in said housing and having its inner end abrupt on both sides and adapted to occupy the notch in the ring and positively lock the ring at a time when an internal groove in the ring is out of registration with a notch through said flange, a chaser frame having a cylindrical sleeve adapted to occupy said movable ring and provided with 120 125 130

a rigid external rib adapted to pass through the notch in the flange into the internal groove of the movable ring, said rib being adapted to pass behind the flange when the 5 movable ring is turned about its axis, and chasers carried by the chaser frame.

5. In a die stock, the combination of a handle frame, a rotative ring carried thereby, a plunger engaging said ring, a holder 10 for chasers having a sleeve portion occupy-

ing the ring, having a cup-like portion at the side of the handle frame, said cup-like portion having radial openings in its wall, radial chasers occupying said opening, bolts passing through the chasers respectively, 15 and each threaded into portions of the head.

In testimony whereof I hereunto affix my signature.

MILTON W. BECHTEL.
